Florence S. Knoll, New York, N.Y., assignor to Knoll Associates, Inc., New York, N.Y., a corporation of New York

Original design application Feb. 18, 1960, Ser. No. 59,437, now Patent No. D. 191,273, dated Sept. 5, 1961. Divided and this application July 3, 1961, Ser. No. 65,796

Term of patent 14 years

(Cl. D33—19)

Fig. 1.

Fig. 2.

Fig. 3.

FIG. 1 is a front elevational view of a file drawer face panel showing my new design;

FIG. 2 is a fragmentary cross-sectional view taken on the line 2—2 of FIG. 1, on an enlarged scale, showing the drawer pull design;

FIG. 3 is a fragmentary cross-sectional view taken on the line 3—3 of FIG. 1, showing the design of the label support.

The relative thickness of the face panel is shown by FIGS. 2 and 3 and the top or upper edge of the panel is plain.

This application is a division of my copending appli-

cation Serial No. D. 59,437, filed February 18, 1960, now Patent No. D. 191,273, issued September 5, 1961.

I claim:

The ornamental design for a file drawer face panel, as shown and described.
